UNITED STATES PATENT OFFICE

ANNA V. GRUNDMANN, OF FARIBAULT, MINNESOTA, ASSIGNOR TO MICHAEL G. GRUNDMANN, OF FARIBAULT, MINNESOTA

SHOE

Application filed August 16, 1927. Serial No. 213,357.

This invention relates to a shoe and a method of making the same, one of the objects being to provide a shoe of the turn sole type in which the channel ordinarily provided and which weakens the shoe, is eliminated with the result that the shoe will give much longer wear than could otherwise be expected.

A further object is to provide a shoe utilizing an inside welt which not only serves to strengthen the shoe but also acts as a support or rest for the channel guide while the upper is being fastened to the sole.

A still further object is to provide a sole having an integral lip to the outer side of which is connected the upper while the welt is designed to overlie the lip upon the completion of the stitching operation, thereby to hold the upper securely to the sole.

A further object is to so arrange the parts that when they are properly assembled they will provide a smooth surface for supporting the tread of the foot.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown.

In said drawings,

Figure 1 is a section through a sole showing the side portions split laterally to provide lips, one of the lips being upturned.

Figure 2 is a section through one side portion of the sole showing one of the lips upturned and a welt stitched in position.

Figure 3 is a similar view showing the lip bent back and stitched in place for use in lieu of a separate welt.

Figure 4 is a view similar to Figure 2 showing the parts held together by an adhesive instead of by stitches.

Figure 5 is a view similar to Figure 3 showing the parts held in position by an adhesive instead of stitches.

Figure 6 is a section through a portion of a last with the sole attached thereto and the upper connected to the sole wherein a separate welt is stitched in place.

Figure 7 is a similar view showing the sole and upper assembled with a downturned lip such as shown in Figure 3.

Figure 8 is a view similar to Figure 6 showing the lip and the marginal portion of the upper trimmed off.

Figure 9 is a view similar to Figure 7 showing the upper trimmed off at its free edge.

Figure 10 is a view similar to Figure 8 showing the relative positions of the parts after the shoe has been turned.

Figure 11 is a view similar to Figure 9 showing the positions of the parts after the shoe has been turned.

Figure 12 is a view similar to Figure 10 showing an insole in position.

Figure 13 is a view similar to Figure 11 showing an insole in position.

Figure 14 is a view similar to Figure 10 but showing the upper stitched to the lip.

Referring to the figures by characters of reference 1 designates the leather sole of a shoe provided with lateral incisions 2 along the edges thereof forming lips 3. Each lip is adapted to be upturned as shown in Figure 2.

Thereafter, if desired, a welt 4 may be stitched to the sole as shown at 5 so as to engage the inner side of lip 3. If preferred, however, the lip can be turned downwardly onto the sole as shown at 6 in Figure 3 and then stitched in place, thus dispensing with the use of a welt.

Instead of stitching these parts in place, however, the welt 7 can be held in position by an adhesive indicated generally at 8 or, if the lip is downturned, as shown at 8', it can be held in place on the sole by an adhesive indicated generally at 9.

In either case the upper is arranged on a last L to which the sole has been tacked as shown in Figures 6 to 9 inclusive and the marginal portions of the upper are placed in the recesses provided by the incisions 2 so as to abut against the lip.

The upper has been indicated at 10 and the inturn portions thereof have been indicated at 11. The marginal portions of the uppers can be extended along the up-

100

standing lips 2 if arranged as in Figure 6 but, if the lips are downturned as in Figures 3 and 5 the marginal portions of the uppers will be extended upwardly away from the downturned lip as shown in Figure 7. In either case the uppers are held in place by stitches indicated at 12 which enter the angles formed by the inturned portions 11 and the marginal portions 13 of the uppers and, in the structure illustrated in Figure 6 pass between the stitches 5 and are exposed in the upper surface of the sole 1 at points close to the inner edges of the welt 4. The same arrangement is noted in the structure illustrated in Figure 7, with the exception that the stitches appear at the inner edges of the downturned lip 6 which of course takes the place of the welt 4. After the parts have thus been connected the lip 3 and the marginal portion 13 of the upper are trimmed off flush with the welt 4 or, where the structure shown in Figure 7 is used, the marginal portion of the upper is cut off flush with the downturned lip 6. These arrangements have been shown in Figures 8 and 9 respectively. Following this step the shoe is turned to bring the parts to the positions shown in Figures 10 and 11 and thereafter an insole 14 is placed in position as shown in Figures 12 and 13.

30 Instead of stitching the uppers through the sole so that the inner portions of the stitches will appear adjacent the inner sides of the welt, the upper can have its marginal portion upturned as shown at 15 in Figure 14 where it will lie against the outer side of the upturned lip 16 of the sole 17. Stitches 18 can be extended transversely through these engaging portions 15 and 16.

It will be obvious that by extending the 40 stitches 12 through or between the stitches 5 the parts are doubly reinforced and held more securely than would be possible should any other arrangement of stitches be employed.

What is claimed is:

45 1. In a shoe the combination with a sole having an inwardly extending incision providing an upturned marginal lip, an upper abutting against the outer surface of the lip, said upper being inturned against the lip, and stitches extending through the inturned marginal portion of the upper and into the upper portion of the sole, said stitches extending under the lip and through the inner surface of the sole, and a welt upon the sole 50 against the inner side of the lip.

2. In a shoe the combination with a sole having an inwardly extending incision providing an upturned marginal lip, an upper abutting against the outer surface of the lip, said upper being inturned against the lip, and stitches extending through the inturned marginal portion of the upper and into the upper portion of the sole, said stitches extending under the lip and through the inner surface 55 of the sole, a welt upon the sole against the

inner side of the lip, and stitches extending through the welt and sole and through the first named stitches.

In testimony that I claim the foregoing as my own, I have hereto affixed my signature.

ANNA V. GRUNDMANN.
